UNITED STATES PATENT OFFICE.

CHARLES MEYER AND HENRY B. MEADE, OF LOS ANGELES, CALIFORNIA, ASSIGNORS
TO FRANK A. GILLESPIE, OF LOS ANGELES, CALIFORNIA.

AMALGAMATOR AND SEPARATOR.

Original application filed January 26, 1921, Serial No. 440,186. Divided and this application filed June 2, 1921. Serial No. 474,344.

To all whom it may concern:

Be it known that we, CHARLES MEYER and HENRY B. MEADE, citizens of the United States, residing at Los Angeles, in the 5 county of Los Angeles and State of California, have invented new and useful Improvements in Amalgamators and Separators, of which the following is a specification.

10 Our invention relates to an amalgamating or metal separating apparatus of the type that is particularly designed for the handling of placer material that carries a certain percentage of so-called black sand, 15 which latter, it will be understood, usually includes base metals such as iron, hematite and the like.

The particular objects of our invention are to generally improve upon and simplify the 20 construction of the existing types of amalgamators and particularly those designed for the handling of placer material; to provide a construction wherein an apparatus of given size has a relatively large material 25 handling capacity, and at the same time is economical in operation; to provide relatively simple and novel means for insuring the separation and collection of the relatively finer or microscopic particles of precious 30 metals; and further, to provide in an amalgamating apparatus relatively simple and efficient means for removing particles of iron, hematite, and the like, usually in the form of black sand, from a recovering or 35 amalgamating agent, such as mercury or the like.

Our present application is a division of our copending application filed January 26, 1921, Serial No. 440,186, and should be 40 read and considered in connection therewith.

With the foregoing and other objects in view, our invention consists in certain novel features of construction and arrangement of parts that will be hereinafter more fully 45 described and claimed, and illustrated in the accompanying drawings, in which—

Figure 1 is a diagrammatic view of our improved amalgamator and separator, with parts thereof in side elevation and in vertical section.

Fig. 2 is a plan view of the right hand end portion of the form of apparatus that is illustrated in Fig. 1 and showing the

means for automatically removing the black sand from the tailings or waste material. 55

Fig. 3 is an enlarged cross section taken approximately on the line 3—3 of Fig. 2.

Fig. 4 is an enlarged vertical section taken approximately on the line 4—4 of Fig. 2.

Fig. 5 is an enlarged cross section taken 60 on the line 5—5 of Fig. 3.

Referring by numerals to the accompanying drawings, which illustrate a practical embodiment of our invention, 10 designates a mixing box or launder which receives the 65 material to be acted upon through a chute 11 and water through a supply pipe 12. Located within the box or container 10 are baffle plates 13, the lower edges of which are spaced apart from the bottom of said 70 box, and the upper edges being connected by a screen 14. Depending from the bottom of the box adjacent to the end in which the baffle plates are located is a pulp discharge pipe 15, and leading into the box or 75 launder above this discharge pipe is a nascent or regenerated mercury supply pipe 16. This mercury supply pipe leads from a mercury regenerating apparatus that includes a tank or container 17 in which is 80 arranged a cathode plate 18 and an anode plate 19, said plates being electrically connected to a suitable source of current supply, such as a generator 20. Located adjacent to the mercury regenerating tank or container 17 is a sodium solution tank 21 in 85 which is arranged for operation a pump 22, preferably of the rotary type and having a discharge pipe 23 that leads into one side of the regenerating tank 17 above the plates 90 therein. Leading from the opposite side of tank 17 is an overflow or outlet pipe 24 that extends to the upper end of an inclined straining tank or receptacle 25, and leading from a chamber below the strainer therein 95 is an outlet pipe 26 that discharges directly into an intake pipe 27 and which latter leads to the lower portion of solution tank 21. Leading from the waste chamber of the straining tank 25 is a waste discharge pipe 100 28. Extending from the lower end of a pocket or receptacle 29 that is located adjacent to the discharge end of a mercury elevator 30 of the regenerating tank 17 and at a point above the plates therein is 105 a mercury conveying tube 31. The lower

end of the mercury elevator 30, which is of the type comprising an endless conveyor on which is arranged buckets, operates in a boot or pocket 32 that is located adjacent to the trough through which the pulp or slimes pass, and leading to said boot from a metal-free mercury receptacle 33 is a mercury conveying tube 34.

All of the parts just mentioned are described in detail in our co-pending patent application above referred to, and while said parts are essential to the successful operation of our improved apparatus we do not in this application make specific claims to said parts.

Our improved placer material handling apparatus includes an elongated trough or launder 35, the higher end of which is positioned beneath the pulp discharge pipe 15, and arranged in said higher end is a series of riffles 36 of step formation, the upper surfaces of which are covered with plates 37 of suitable material, preferably copper.

Arranged immediately above these riffles and disposed substantially parallel with the inclined plane in which they are located is a plate 38 from which depends a series of curved baffle or retarding plates 39, and which latter are preferably formed of copper.

Plate 38 is adjustably suspended from a frame 40 in order that it may be swung longitudinally in both directions so as to position the lower ends of the curved baffle plates 39 at different distances away from the ends of the riffles.

Plate 38 may be provided with any suitable means for swinging it lengthwise and for locking it after proper adjustment, and in Fig. 1 we have shown an adjusting and locking means that includes a handle 41 that is pivotally connected to said plate 39 and said handle carrying a transverse pin 42 that is adapted to be engaged in any one of a series of notches 42' that are formed in a fixed part of frame 40.

Arranged in the bottom of trough 35 a short distance below the lower end of the series of riffles is a series of transversely disposed channel-shaped members 43, the pockets 44 of which are adapted to receive the amalgam or metal carrying mercury as the same flows downwardly over the inclined bottom of said trough 35, and the bottom of each pocket 44 is inclined lengthwise so that said amalgam or mercury will by gravity gradually flow toward the lower end of said pocket. Metal plates 45, preferably copper, are applied to the upper face of the bottom of the trough 35 between the channel-shaped members 43 and said plates are arranged so that their lower edges overlie the upper side walls of said members 43, while on the opposite or lower sides of the channel-shaped members the edges of said plates 45 are

spaced apart from said members 43, as designated by a Figs. 5 and 7. This arrangement forms shallow depressions immediately below the channel-shaped members, which depressions greatly facilitate the flow of the amalgam that travels across the amalgam-filled pockets while the apparatus is in operation.

Where a relatively narrow trough 35 is made use of the channel-shaped members 43 extend from one side wall of the trough across the bottom thereof and through the opposite side wall, as illustrated in Figs. 7 and 8, but where the trough is of considerable width a pair of the channel-shaped members are arranged in direct alinement with each other on opposite sides of the medial line of the trough so that the amalgam will flow from the center in opposite directions toward both sides of the trough.

Blocks 48 (Fig. 1) are arranged at the ends of the channels 43 where the pockets 44 are of the greatest depth.

Transversely arranged in the bottom of trough 35 between the lower one of the channel-shaped members 43 and the lower end of said trough is a series of transversely disposed shallow troughs 63 and the ends thereof on one side of said trough 35 communicate with a longitudinally disposed trough 64 that is positioned directly against the side wall of said trough 35.

Arranged for operation in the upper portion of each trough 63 is a relatively small screw conveyor 65 and on the side of trough 35 opposite the side to which trough 64 is applied the ends of these screw conveyors are provided with sprocket wheels 66, over which travels a sprocket chain 67. This sprocket chain is driven from a sprocket wheel 68 that is fixed on the end of a shaft 69 and the latter being journaled in suitable bearings on the trough 35 and carrying a larger sprocket wheel 70.

Journaled in suitable bearings in the upper portion of the side walls of trough 35 is a shaft 71 on which is mounted a drum 72, from the periphery of which projects vanes or blades 73 that are adapted to be engaged by the pulp as it flows through the lower portion of trough 35. Fixed on shaft 71 is a sprocket wheel 74 and connecting the latter with sprocket wheel 70 is a sprocket chain 75.

By virtue of this construction the pulp flowing through the lower portion of trough 35 rotates drum 72 and the motion thereof will be transmitted through the driving connections just described to shaft 69 and from thence through sprocket chain 67 to all of the sprocket wheels 66, and as a result all of the screw conveyors 65 will be simultaneously rotated.

Shaft 69 extends through troughs 35 and 64 and mounted upon said shaft within the

trough 64 is a sprocket wheel 76, around which passes a sprocket chain 77, the latter extending lengthwise through said trough 64 and being supported by suitably located 5 sprocket wheels 78. This sprocket chain carries plates 79 that are adapted to scrape over the bottom of trough 64 and carry any material that may be delivered thereinto to one end thereof, (see Fig. 4).

10 The operation of our improved amalgamator is as follows:

The metal bearing material in pulverized form is delivered into tank or launder 10, and after being mixed with water that enters through pipe 12, said material in pulp form discharges through pipe 15 and flows downwardly through trough 35 over the riffles 36 therein. As this operation takes place nascent or regenerated mercury discharges from pipe 16 and passes downwardly with the pulp into the tank or launder 35. As the pulp flows over the step riffles, the mercury and heavy material intermingled with said pulp will by gravity pass 25 downward onto the amalgam plates covering said step riffles, and the lighter portion of said pulp, or that portion at and near the top of the volume flowing over the riffles, will be engaged by the lower portions of the 30 curved baffle plates 39 and thus turned over, so that any relatively fine particles of metal that are carried in suspension in the lighter portion of the pulp will, at some time during its passage downwardly over the step 35 riffles, be brought into contact with one of the baffle plates, thereby amalgamating with the mercury thereupon.

Inasmuch as the baffle plates 39 and the surfaces of the plates 37 on the riffles are 40 coated with mercury, practically all the particles of material in the pulp will be brought into contact with a mercury coated surface while passing over said riffles and beneath the curved plates, with the result 45 that the mercury on said plates will amalgamate with or take up the free particles of metal. This metal-containing mercury, after leaving the riffles, flows downwardly over the metal-covered bottom of the trough 50 or launder and finally passes into the pockets 44 in the transverse channel-shaped members 43, and said mercury, by gravity, flows towards the lower ends of said pockets and into the pockets of the blocks 48. The mercury bearing the heavier metals, will, by 55 gravity, separate from the mercury bearing the lighter metals and from the metal-free mercury in passing through the pockets of the blocks 48, and for a more complete description of this separating operation and the subsequent handling of the metal-free mercury and the regeneration thereof, reference may be had to our above mentioned co-pending application.

60 After passing over the series of pockets

44 the pulp containing the so-called black sands passes over the channel-shaped members 63 in which are arranged the screw conveyors 65. Each member 63 contains a body of mercury below the screw conveyor, which 70 mercury performs the functions of a mobile cushion for the material such as black sand that enters the pocket occupied by the conveyor, and as the conveyor is rotated the material within the pocket and which lies on 75 top of the body of mercury therein, will be moved lengthwise through the channel-shaped member and finally discharged into trough 64.

It will be understood that all of the screw 80 conveyors 65 will be simultaneously rotated by the driving connections from wheel or drum 72, the plates of which are engaged by the pulp flowing through the lower portion of trough 35, and simultaneously the 85 scraper-carrying chain 77 operating in said trough 64 will be operated to scrape all material that is discharged into said trough toward one end of the latter, and from whence it may discharge into a suitably located receptacle.

Thus it will be seen that we have provided a relatively simple and efficient apparatus for the very rapid and economical handling of placer material to effect the separation of 90 all metallic values therefrom and also for removing from said placer material all low grade metals, such as iron, hematite and the like, which usually take the form of the so-called black sand.

Obviously, minor changes in the size, form and construction of the various parts of our improved amalgamator and separator may be made and substituted for those herein shown and described without departing 105 from the spirit of our invention, the scope of which is set forth in the appended claims.

We claim as our invention:

1. In an amalgamator, a trough through which the material to be treated is adapted to pass, a series of mercury pockets in the bottom of said trough, screw conveyors arranged for operation in the trough for removing the material that collects within the pockets, a receptacle adapted to receive the 110 material removed from the mercury pockets by the conveyors therein, and means for removing the material from said receptacle.

2. An amalgamator comprising a trough through which metal bearing material is adapted to pass, said trough being provided with a mercury containing pocket, a receptacle adjacent the trough, a spiral conveyor for discharging material accumulating on the mercury into the receptacle, and means actuated by the flow of material through the trough for operating the conveyor.

3. In an amalgamator, a trough through which the metal bearing material is adapted to flow, there being a series of transversely 130

disposed pockets formed in the bottom of said trough, which pockets are adapted to contain mercury, a receptacle on the side of the trough, the chamber within which receptacle communicates with the pockets in the bottom of the trough, and spiral conveyers arranged for operation within said pockets and adapted to move material that may collect in said pockets on top of the mercury 10 therein into the receptacle on the side of the trough.

4. In an amalgamator, a trough through which the metal bearing material is adapted to flow, there being a series of transversely disposed pockets formed in the bottom of said trough, which pockets are adapted to contain mercury, a receptacle on the side of the trough, the chamber within which receptacle communicates with the pockets in 15 the bottom of the trough, and means actuated by the flow of material through the trough for moving material that may collect in the mercury pockets into the receptacle at the side of the trough.

5. In an amalgamator, a trough through which the metal bearing material is adapted to flow, there being a series of transversely disposed pockets formed in the bottom of said trough, which pockets are adapted to 20 contain mercury, a receptacle on the side of the trough, the chamber within which receptacle communicates with the pockets in the bottom of the trough, spiral conveyers arranged for operation within said pockets and adapted to move material that may collect 25 in said pockets on top of the mercury therein into the receptacle on the side of the trough, and means for effecting the discharge of material from said receptacle.

6. In an amalgamator, a trough through which the metal bearing material is adapted to flow, there being a series of transversely disposed pockets formed in the bottom of said trough, which pockets are adapted to 30 contain mercury, a receptacle on the side of the trough, the chamber within which receptacle communicates with the pockets in the bottom of the trough, means actuated by the flow of material through the trough for operating the first means, and means actuated by the flow of material through the trough for effecting the discharge of material from 35 said receptacle.

50

the trough, and means for effecting the discharge of material from said receptacle.

7. In an amalgamator, a trough through which metal bearing material is adapted to 55 pass, a transversely disposed pocket arranged in the bottom of said trough adapted to contain mercury, a spiral conveyer arranged for operation within said pocket above the surface of the body of mercury 60 therein, and means actuated by the flow of material through the trough for rotating said spiral conveyer.

8. In an amalgamator, a trough through which metal bearing material is adapted to 65 pass, a transversely disposed pocket arranged in the bottom of said trough adapted to contain mercury, a spiral conveyer arranged for operation within said pocket above the surface of the body of mercury 70 therein for removing material from said pocket, means actuated by the flow of material through the trough for rotating said spiral conveyer, and means for collecting any material discharged from said pocket 75 by said conveyer.

9. An amalgamator comprising a trough through which metal bearing material is adapted to pass, said trough being provided with a mercury containing pocket, a receptacle adjacent the trough, means for discharging material accumulating on the mercury into the receptacle, means actuated by the flow of material through the trough for 80 operating the first means, and means actuated by the flow of material through the trough for effecting the discharge of material from said receptacle.

10. An amalgamator comprising a trough through which metal bearing material is adapted to pass, said trough being provided with a pocket adapted to contain mercury, a receptacle at one end of and at right angles to the trough, a conveyor for discharging the material accumulating on the mercury 95 into the receptacle, and means actuated by the flow of material through the trough for operating the conveyor.

In testimony whereof we have signed our names to this specification.

CHAS. MEYER.
HENRY B. MEADE.
